UNITED STATES PATENT OFFICE.

DONALD FRASER AND SAMUEL SHAFER, JR., OF MILWAUKEE, AND CHRISTOPHER W. LEVALLEY, DECEASED, LATE OF MILWAUKEE, WISCONSIN, BY HELEN P. LEVALLEY, OF MILWAUKEE, WISCONSIN, AND WISCONSIN TRUST COMPANY, A CORPORATION OF MILWAUKEE, WISCONSIN, EXECUTORS, ASSIGNORS TO CHAIN BELT COMPANY, OF MILWAUKEE, WISCONSIN, A CORPORATION OF WISCONSIN.

APPARATUS FOR CONVEYING AND DELIVERING MATERIAL.

1,422,687.

Specification of Letters Patent. Patented July 11, 1922.

Application filed January 6, 1920. Serial No. 349,777.

To all whom it may concern:

Be it known that DONALD FRASER and SAMUEL SHAVER, Jr., both citizens of the United States, residing at Milwaukee, in 5 the county of Milwaukee and State of Wisconsin, and CHRISTOPHER W. LEVALLEY, deceased, late a citizen of the United States, and a resident of Milwaukee, in the county of Milwaukee and State of Wisconsin, have 10 invented certain new and useful Improvements in Apparatus for Conveying and Delivering Material, of which the following is a specification.

This invention relates to apparatus for 15 conveying and delivering material, and has been designed with especial reference to receiving and conveying concrete from a mixing machine, and delivering it directly from the transporting bucket or other receptacle, at the bottom of a deep hole, such as the excavation for a concrete pile or a deep foundation. It has been discovered that when concrete is poured from the surface of the ground into a deep hole, there 20 is a tendency for the several ingredients forming the concrete mixture to separate more or less, with the result that the delivered material does not have that homogeneity which is most desirable; and one of the 25 objects of the invention is to overcome this objection.

In the accompanying drawings—

Figure 1 is a side elevation of an apparatus embodying the invention; 30 Fig. 2 is an end view of the apparatus, parts being in transverse vertical section;

Fig. 3 is a side elevation, drawn on a larger scale than Fig. 1, and showing parts of the boom and bucket and the carriage 40 and associated parts by which the bucket is supported from the boom and by which the movements and operation of the latter are controlled.

Fig. 4 is an end view of the parts illustrated in Fig. 3, the boom and traversing cable being in cross section.

Fig. 5 is a longitudinal sectional view of the parts illustrated in Fig. 1, the bucket being omitted.

50 In such drawings a portion only of a concrete mixing machine is represented, this being designated 2. 3 indicates the

framework located near the discharge end of such machine. In a bracket 4 supported by the said framework, is mounted the 55 vertical pivot or bearing for a boom 5 that constitutes the track or way along which travels a trolley or carriage 6 from which is suspended the bucket 7, or other receptacle for receiving and transporting the 60 mixed concrete, which is delivered thereto from the mixing machine through a spout 8. The trolley is caused to traverse the boom by a chain belt or cable 9 that is 65 suitably connected with the carriage and is 70 driven through mechanism 10, connected with the prime motor through intermediate mechanism not necessary here to describe, and under the control of the attendant operating the machine.

The parts thus far described, in their general features, may be of any usual or preferred construction.

The bucket is provided with a pair of ears 11 in which is mounted a shaft 12, that 75 carries a sheave 13. The cable 15 by which the bucket is raised and lowered, engages with the sheave 13 and with other sheaves 14, 14, mounted in the trolley or carriage 6 and between which the sheave 13 is 80 located.

16, 16 represent hooks supported upon a shaft 17 mounted in the frame of the trolley, the hooks being arranged to engage with the shaft 12 and serving as the means 85 through which the bucket is connected with and suspended from the trolley. Springs 19 act upon the hooks 16 and tend to force them into position to engage with the shaft 12. An arm 18 extends from the shaft 17 in position to engage with an adjustable stop 20 that may be secured to the boom in any desired position. The engagement of the arm 18 with this stop, as the trolley moves outward along the boom, rocks the shaft 17 and 90 causes the hooks 16 to disengage the shaft 12, whereupon the bucket is suspended only by the cable 15 and may then be lowered by letting out the cable.

One end of this cable 15 is made fast to some suitable part of the apparatus, as to the boom at the point 21, whence it extends forward over one of the sheaves 14 in the trolley; thence under the sheave 13 carried by the bucket; thence over

the other sheave 14 in the trolley, and forward to pulleys 22 at the forward end of the boom; and thence rearward along the boom and past guide pulleys 23 to a winding 5 drum 24 supported in the framework 3, to which the cable is secured. This drum is mounted upon a shaft 25 in driving connection, through suitable gearing 26, with the 10 motor, and controlled by clutch and brake mechanism 27 that may be operated by the attendant. It will thus be seen that whenever the bucket is released from the hooks 16 that unite it with the trolley, it may be lowered, as into a hole or excavation such 15 as indicated directly below the bucket in Fig. 1, by the attendant allowing the cable to run off from the drum 24.

The bucket is provided with hinged doors 28 through which the material it contains 20 may be discharged. These doors are arranged to open outwardly and are connected by links 29 with a lock link 30, which is pivoted, at 35, to an arm 31 that is secured fast to a shaft 32 supported in the ears 11 of 25 the bucket. The relation of the pivots of the links 29 and 30 to the axis of the shaft 32 is such that when the parts are in the position indicated in Fig. 1, the doors of the bucket are held securely closed by a toggle 30 lock of the parts. But a slight rotative movement of the shaft is sufficient to carry the parts from this locked condition to one which permits the doors to open freely under the action of gravity, and when this 35 occurs, a hook 33 with which the lock link 30 is provided, engages with a cross-bar 45 on the bucket, by which arrangement the doors are held supported in open condition for discharging the contents of the bucket. 40 The doors may be closed manually, and to permit this the shaft 32 is provided with a handle 34. The mechanism employed for releasing the doors and permitting them to be opened when the bucket reaches the point of 45 discharge, as for instance the bottom of the hole or excavation, will now be described.

36 indicates a ratchet wheel secured to the shaft 12. With this ratchet wheel engages a pawl 37 pivotally united at 38 with 50 the arm 31 that is secured to the shaft 32 and to which the lock link 30 is pivotally connected. A spring 39 bearing upon the pawl tends to hold it in yielding engagement with the ratchet wheel 36. The pawl 55 is provided with a toe 41 that, by engagement with a part of the arm 31, operates as a stop to prevent the pawl being thrown too far by the spring 39. An adjustable stop 40 mounted in a bearing carried by 60 one of the side frame pieces of the carriage 6 is also arranged to control the position of the pawl.

42, 42 indicate the skirts of the trolley 6. These overhang the upper ends of the 65 bucket ears 11, which are preferably bifur-

cated to form arms 44, 44, that are adapted to enter recesses 43 in the skirts of the trolley when the bucket is drawn up and engaged by the hooks 16, and prevent rocking or vibration of the bucket as it traverses the boom.

The operation of the apparatus is as follows: The trolley is run inward, or toward the concrete mixing machine, along the boom until the bucket is brought into position to receive material through the spout 8. After the bucket has been charged it is run out along the boom to a position above the excavation into which the charge is to be delivered. Here the trolley is brought to rest at 75 the same time that the contact arm 18 engages with the adjustable stop 20 and the hooks 16 are moved to disengage the shaft 12 and release the bucket from the trolley, except as it is held suspended by the cable 80 15. The cable is now allowed to run off from the drum 24 and the bucket lowered into the excavation. As it does so the sheave 13 and ratchet wheel 36 rotate in the direction of the arrow *a*, Fig. 5. In turning 90 in this direction, the ratchet moves freely past the pawl 37. When the bucket has descended to the desired place of discharge, the attendant connects the drum 24 with the motor and starts the winding of 95 the cable upon the drum, which reverses the direction of rotation of the sheave 13 and the ratchet wheel 36.

The teeth of the ratchet wheel now engage with the pawl 37, which is caused to travel 100 forward with the wheel, moving bodily therewith and operating to turn the arm 31 about its axis which is the center of the shaft 32. This movement also swings the pivotal connection 35 uniting the lock link 105 30 to the arm 31, until the toggle lock for the doors of the bucket is broken, when they will be instantly forced open by the weight of the contents of the bucket, which are thereupon discharged, such discharge taking place at the vertical position occupied by the bucket when the direction of movement of the cable 15 was reversed, whatever that position be with reference to the supporting track of the carriage 6. The 110 movement of the link 30 and of the arm 31, due to the opening of the doors, carries the pawl 37 entirely out of engagement with the ratchet wheel 36, and it remains in this position until restored to engagement with the 115 ratchet wheel, as by turning the handle 34 to relock the doors.

What we claim is:

1. The combination of a track, a carriage arranged to traverse the track, a bucket capable of being discharged suspended from the carriage, means for causing the carriage to traverse the track, means for controlling the raising and lowering of the bucket relative to the carriage, and means for causing 125 130

the discharge of the bucket while suspended, at any position within the range of vertical movement of the bucket, over the desired place of deposit, operated by the means that 5 control the raising and lowering thereof.

2. The combination of a track, a carriage arranged to traverse the track, a bucket capable of being discharged supported from the carriage, and adapted to be raised and 10 lowered relative to the carriage, means for causing the carriage to traverse the track, a cable for supporting the bucket, and by which its raising and lowering are controlled, and means for causing the discharge 15 of the bucket while suspended by the cable arranged to be operated by the cable when its direction of movement is reversed.

3. The combination of a track, a carriage arranged to traverse the track, a bucket 20 capable of being discharged supported from the carriage, means for holding the bucket in condition to contain its load, means for causing the carriage to traverse the track, a cable for supporting the bucket, means for 25 controlling the movements of the cable to raise and lower the bucket, a sheave about which the cable passes movable up and down with the bucket, and means operated from said sheave for causing the discharge of the 30 bucket when the cable is moved to raise the same.

4. The combination of a bucket capable of being discharged, a cable for supporting the bucket, means for controlling the movements of the cable in order to raise and lower the bucket, a rotatable sheave carried by the bucket with which the cable engages and which is turned thereby as the cable is moved to raise or to lower the bucket, and 40 means for causing the discharge of the bucket operated from the said sheave when it is turned in one direction.

5. The combination of a bucket capable of being discharged, a cable for supporting the 45 bucket, means for controlling the movements of the cable in order to raise and lower the bucket, a rotatable sheave carried by the bucket with which the cable engages, and means for causing the discharge of the 50 bucket when the sheave is first turned on the movement of the cable to raise the bucket.

6. The combination of a bucket provided with doors that control its discharge, means for holding the doors closed, a cable for supporting the bucket, means for controlling the movements of the cable in order to raise and lower the bucket, a rotatable sheave carried by the bucket with which the cable engages, and means operated from the said 55 sheave when it is turned in one direction for releasing the said doors and permitting the bucket to discharge.

7. The combination of a bucket, doors by which the discharge of the bucket is controlled, a cable for supporting the bucket, 60

means controlling the movements of the cable in order to raise and lower the bucket, a rotatable sheave carried by the bucket with which the cable engages, a ratchet wheel turning with the sheave, means including a 70 pawl engaging with the said ratchet wheel for releasing the doors and permitting the bucket to discharge, operated when the sheave turns in one direction.

8. The combination of a track, a carriage 75 arranged to traverse the track, a bucket supported from the carriage, means for causing the carriage to traverse the track, hinged doors controlling the discharge of the bucket, a sheave carried by the bucket, a ratchet 80 wheel turning with the sheave, a toggle lock for holding the doors closed, a spring pawl engaging with the ratchet wheel arranged to break the lock when the ratchet wheel turns in one direction, and a cable for raising and lowering the bucket passing about the said sheave.

9. The combination of a track, a carriage arranged to traverse the track, a bucket capable of being discharged, hooks pivotally 90 supported by the carriage for connecting the bucket therewith, means for causing the carriage to traverse the track, an adjustable stop adapted to be secured to the track at any desired point, arranged to throw off the 95 hooks and release the bucket from the carriage as the latter comes to the place where the stop is secured, a cable for supporting the bucket when released from the said hooks, means for controlling the movements of the 100 cable for raising and lowering the bucket, and means for causing the discharge of the bucket arranged to be operated when the direction of movement of the cable is reversed to change from the lowering to the 105 raising movement of the bucket.

10. In an apparatus for delivering material, the combination of a track, a carriage arranged to traverse the track, a bucket capable of being discharged, means for maintaining the bucket in condition to contain its load, a cable for suspending the bucket and by which it is raised and lowered, means for uniting the bucket with the carriage during transit, means for automatically releasing the bucket from the said uniting means when the carriage reaches the desired point along the track, means for controlling the movements of the cable to raise or lower the bucket, and means arranged to cause the 110 120 bucket to discharge its load while suspended by the cable, such means being operated by movement of the cable in the direction to raise the bucket.

11. The combination of a track, a carriage 125 adapted to traverse the track, a bucket capable of being discharged suspended from the carriage, means for controlling the movements of the carriage along the track, means for releasing the bucket from the carriage to 130

permit it to descend, means for controlling the raising and lowering of the bucket, and means for causing the discharge of the bucket when it begins to rise.

5 12. The combination of a track, a carriage arranged to traverse the track having skirts in the lower edges of which are formed recesses, and a bucket suspended from the carriage provided with bifurcated ears, the 10 arms of which are arranged to engage with the recesses in the skirts of the carriage,

whereby the swinging of the bucket relative to the carriage is prevented.

DONALD FRASER.
